INVENTOR

UNITED STATES PATENT OFFICE.

CLARENCE LIVINGSTON BURGHER, OF NEW YORK, N. Y.

SOAP CAKE.

Application filed January 17, 1925. Serial No. 3,019.

My invention has for its object to provide a soap cake which will afford a hold for the hand, and thus not easily slip out of the hands when wet, as constantly happens resulting in much loss of time and temper.

The reason that soap when wet slips out of the hand easily is that the cake is usually flat or exteriorly tapering, so that, particularly in the latter case, the harder the hand squeezes it, the greater the tendency to wedge it out of the hand.

The ordinary shallow markings on soap cakes are soon worn down, and do not afford any real hold for the hands when the soap is wet.

I discovered some time ago that by forming a substantial hollow, recess or chamber to receive the fingers or palm of the hand, preferably in both sides of the soap cake and in the middle thereof, and preferably so that the recesses on both sides almost meet so as to leave a mere web therebetween, the interiorly facing shoulders or slopes formed by the hand-hollow, recess or chamber, will serve as an effective hold or grip for the hands, until the soap is practically worn to a wafer, and the harder the soap is squeezed by the hand, the greater the tendency of the soap cake to stay in the hand owing to the wedge-like effect of the interiorly facing shoulders or slope being inward instead of outward as in the ordinary soap cake.

In order that my invention may be fully understood, I shall first describe in detail the mode in which I at present prefer to carry the same into effect and then particularly point out the various features of the invention in the claims.

Reference is to be had to the accompanying drawing forming part of this specification in which like parts are designated by the same numbers in all the figures.

Figure 1 is a face view of a circular soap cake embodying my invention in its present preferred form.

Figure 2 is a cross sectional view of the same, on the line 2—2 Figure 1.

Figure 3 is a face view of an oval soap cake embodying my invention in its present preferred form.

Figure 4 is a face view of a squared soap cake embodying my invention in its present preferred form.

In making a cake of soap, according to

my invention, I form by means of a properly shaped mold or press in the side of the cake, a hole, cavity, recess, chamber or sink, all which, as well as every equivalent formation, I call a recess 5, of a size, contour and depth sufficient to receive a substantial portion of the fingers or palm of the hand, and thus afford the hand a substantial hold or grip on the squared, sloping, rounded or otherwise shaped shoulder 6 formed by the side of the recess. This shoulder 6 facing as it does interiorly or toward the center of the cake tends to keep the wet cake in the hand the more securely the more strongly the soap is squeezed, as the wedge-like effect of the hand on said shoulder tends to press the cake into the hand, whereas in the ordinary cake of soap the effect is exactly the reverse so as constantly to force the wet soap out of the hand.

If the recess 5, extends completely through the soap so as to form an annular cake; or the recess is formed in one side only of the cake leaving a thin web on the other side; or the recess is not in the middle of the cake as here shown but eccentric; or the recess is of a different contour from the outside of the cake, the broad purpose of my invention is served and such modifications are within the scope of my invention, excepting that the form of cake having the hand-receiving opening and the surrounding shoulder of soap extending completely and continuously through the cake will be made the subject of a separate application for patent. Up to the present time, however, I have found that the purpose of my invention is much better served by forming like recesses 5 in the middle of the opposite sides of the cake, of a depth sufficient to leave merely a thin web 7 between the floors of the recesses, and of a contour corresponding approximately to the exterior contour of the cake.

The opposite recesses 5 and their shoulders 6 give the hand a lateral hold or grip on both sides of the cake until the cake is worn thin; the web 7 gives a firmer support to and makes a bearing for the hand; the central location of the recess and the contour of the hollow, corresponding to that of the cake itself, makes a better form of hold or grip for the hand as well as facilitating the manufacture and improving the appearance of the soap.

I claim as my invention:

1. A hand-cake of soap having a recess in its mid-portion of such depth as to leave a relatively thin web of soap surrounded by a shoulder of soap, thus forming a hold for the hand.
2. A hand-cake of soap having a recess in the mid-portion of each side of such depth as to leave a relatively thin web of soap in the medial plane of the cake surrounded by shoulders of soap on opposite
3. A hand-cake of soap having a recess in its mid-portion of such depth as to leave a relatively thin web of soap surrounded by a shoulder of soap, which is substantially perpendicular to the plane of the web, thus forming a hold for the hand.

In testimony whereof I affix my signature

CLARENCE LIVINGSTON BURGHER.
